UNITED STATES PATENT OFFICE.

KARL A. WERNLÉ, OF CHICAGO, ILLINOIS, ASSIGNOR TO JAMES B. CLOW & SONS, OF CHICAGO, ILLINOIS, A CORPORATION OF ILLINOIS.

HANGER FOR WALL CLOSETS.

Application filed May 15, 1926. Serial No. 109,449.

The invention of this application pertains generally to means for securing closet bowls, urinals, sinks and the like in place against a partition wall and more particularly to a means for connecting such articles, vessels or receptacles to a soil or drain pipe, whereby the article, vessel or receptacle is supported through the connection to relieve the wall from the load thereof. The invention in one application and in a preferred form thereof will be described in connection with the closet bowl of the type ordinarily known as a wall closet.

One of the primary objects of my invention is to provide a simple form of supporting connection or hanger of the character indicated above, which may be easily installed and adjusted, one to which the closet bowl or other vessel or receptacle may be readily connected and one which will securely support and rigidly maintain the bowl or other vessel in position independently of but contiguously to the partition wall so that clearance will be provided between the bowl or other vessel and the floor.

Another object is to provide a hanger for the purpose and of the character indicated, simple of construction, arrangement and use, one which may be economically manufactured, one which may be quickly and readily adjusted to, along or about a soil or waste pipe regardless of the thickness of the wall between the closet or other vessel and the hanger and one which will be strong and durable in use.

Many further objects including the constructional details and their arrangement will be or should become apparent from the following description and claims and from the drawing in which:

Fig. 1 is a side elevational view partly in section of a wall closet assembly supported and connected to a main soil pipe through the medium of a hanger constructed in accordance with the invention, and

Fig. 2 is a perspective view of the hanger shown in Fig. 1.

In the drawing, 2 designates a wall closet bowl or any other similar receptacle, 3 a wall or partition against or in proximity to which the bowl 2 is mounted, 4 designates the floor and 5 the main soil pipe connection elbow or T connection. The closet bowl dis-

charge opening 6 is connected through a thimble 7 abutting against a packing 8 disposed in a recess 9 around the discharge opening to a branch soil pipe 10 by means of a gland nut or the like 11 and to the main soil pipe connection 5 through the threaded end 12 of the branch soil pipe. The parts and their arrangement thus described form no part of my present invention per se, as the same may be utilized with various other arrangements and connections, as will be clearly obvious. However, certain of said parts form the subject matter of my Patent No. 1,637,365, dated August 2, 1927, to which reference may be had for further information regarding them.

Very often the wall or partition 3 is thin and weak and will not stand the weight of the ordinary closet bowl or the weight of such bowl with the usual strains imposed upon it. Whether the wall be thin and weak or not, it is desirable that it be relieved from any appreciable strain due to the weight of the bowl or strains imposed upon the bowl and that the weight of the bowl be carried or transmitted directly to the soil pipe. At the same time it is necessary that little or no relative movement between the bowl and the soil pipe branch or connection occur because as soon as this happens the joint between the nipple and the bowl or the like is apt to open and the connection will leak. To adequately support the closet bowl and any strains which may be imposed upon it and to overcome the possibility of appreciable relative movement between the soil pipe branch connection and the bowl, I provide a hanger which is generally designated 13.

This hanger includes a sleeve-like body portion 14 adapted to be slipped over the soil pipe branch or connection 10 and to be adjusted therealong or thereabout to any desirable or necessary position. Projecting substantially radially from what I shall term the forward end of the body portion are a plurality of legs or arms 15 and 16, the legs or arms 16 in this instance being shown as longer than the legs or arm 15 for the type of closet or bowl to which they are to be attached, as will appear.

The legs or arms 15 and 16 of the hanger are preferably drilled and tapped, as shown at 17 and 18, for the reception of stud bolts

19 and 20 which are engaged at their other ends with a rear flange 21 formed integrally with the bowl. The sleeve portion 14 is preferably provided with two ribs 22 which preferably extend the full length of the sleeve and in parallel relation. These ribs are preferably of triangular cross section with an apex thereof lying on a radius from the center of the sleeve portion.

10 Opposed to the ribs 22 is a set screw or the like 23 which serves to clamp the soil pipe branch 10 against the ribs 22 when the hanger is disposed about or embraces the soil pipe branch.

15 In assembling the structure the bowl may be temporarily supported in any suitable manner during the time employed for coupling it to the soil pipe 5. The hanger 13 is disposed over one end of the soil pipe branch and allowed to remain loosely thereon until the stud bolts 19 and 20 are engaged with it and with the rear flange 21 of the bowl. The bowl is, of course, levelled or otherwise adjusted in the position in which 25 it is desired to maintain it, during which operation the hanger through the bolts 19 and 20 will be swung one way or the other about the soil pipe branch because it is loosely positioned thereon. After the bowl has 30 been properly positioned the bolts 19 and 20 may be rotated to adjust the hanger to the proper position fore and aft along the soil pipe branch and when properly positioned the set screw 23 or its equivalent is screwed down against the soil pipe branch to secure 35 the soil pipe branch and hanger rigidly together. If sufficient tension has not been placed on the bolts 19 and 20 and the closet bowl 2 by this operation has not been rigidly 40 secured to the soil pipe branch, the bolts 19 and 20 may be further tightened to impose the requisite tension or pulling action on the closet bowl. The result is that the weight of 45 the bowl 2 and any weight imposed thereon tending to urge the lower portion of the bowl against the wall and to pull the upper portion of the bowl away from the wall or other partition, will place the bolts 20 under compression and the bolts 19 under tension, thus 50 transmitting any torsional tendency or strains of the bowl on the hanger which, by reason of the ribs and set screw 23, will in turn impose the strain upon the soil pipe

branch in a place where it may be most effectively absorbed.

55 While I have illustrated and described a preferred embodiment of my invention in connection with a wall closet bowl it will be appreciated that it is of wider application and susceptible of many changes and variations in details of arrangement and construction. For such reason I do not desire to be limited by what I have shown and described for illustrative purposes but only by the spirit of the invention and the scope 60 of the appended claims.

I claim:

1. A hanger for wall closets comprising, a portion adapted to be secured to a closet, a sleeve connected to said portion and adapted 70 to be loosely disposed about a soil pipe branch, and means for securing said sleeve in a plurality of positions of adjustment along and about said soil pipe whereby to position said portion with respect to the closet comprising, a pair of spaced projections on the interior of said sleeve adapted to contact with the surface of the branch, and a single set screw for drawing the projections and branch tightly together.

75 2. A hanger of the class described comprising, a portion adapted to be connected to closets and the like, a sleeve secured and extending at an angle to the portion and adapted to be loosely disposed about a soil pipe 85 branch and adjustable in one direction with respect to said pipe, spaced ribs on the interior of said sleeve adapted to normally clear said pipe when said sleeve is adjusted with respect to the pipe, and means for urging said ribs and branch relatively toward one another.

80 3. A hanger of the class described comprising, a sleeve adapted to be loosely disposed about a soil pipe branch for adjustment with respect thereto, spaced ribs on the interior of said sleeve, a single set screw for urging said ribs and branch relatively toward one another regardless of the position to which said sleeve may be adjusted, and 100 means for connecting the hanger at a plurality of points to a closet bowl.

In witness of the foregoing I affix my signature.

KARL A. WERNLÉ.
